(57) **CLAIM**

The ornamental design for a heat press pad, as shown and described.

DESCRIPTION

FIG. 1 is a front, bottom and left side perspective view of a heat press pad, showing our new design;

FIG. 2 is a rear, top and right side perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is an enlarged view of portion "9" in FIG. 1.

The broken lines shown in the drawings illustrate portions of the heat press pad that form no part of the claimed design. The dot-dash broken lines in the drawings illustrate boundaries of the enlarged portion that form no part of the claimed design.

1 Claim, 9 Drawing Sheets
